UNITED STATES PATENT OFFICE.

JOHN F. ANDERSON, OF OAKLAND, CALIFORNIA.

SALTING MACHINE.

Original application filed September 18, 1917, Serial No. 191,922. Divided and this application filed January 24, 1921. Serial No. 439,468.

To all whom it may concern:

Be it known that I, JOHN F. ANDERSON, a citizen of the United States, residing at Oakland, in the county of Alameda and State of California, have invented certain new and useful Improvements in Salting Machines, of which the following is a specification.

The present invention is a device applicable to fish-canning and other similar machines for dispensing salt, preserving or other suitable material into the cans or packages in which the product is packed.

This application is a division of my co-pending application, Serial No. 191,922.

It is the object of the present invention to provide a dispensing device of the character above mentioned which is readily applicable to machines of the type shown in my copending application, above mentioned, and which is efficient for its purposes, relatively cheap to produce, and positive and reliable in its operations. These and other objects will be apparent from the following detail description fully setting forth the advantages of the invention and its construction.

In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

In the drawings which illustrate the invention,

Fig. 1 is a vertical sectional view of the salting device,

Fig. 2 is a sectional elevation of the actuating means for the salting device occurring below the table or conveyor 6,

Fig. 3 is a top plan view for the salting device shown in Fig. 1,

Fig. 4 is a transverse sectional view taken substantially on line 4-4 of Fig. 1 and looking in the direction of the arrows; and

Fig. 5 is a transverse sectional view taken substantially on line 5-5 of Fig. 2 and looking in the direction of the arrows.

Referring in detail to the drawings, the salting device comprises a stationary con-

tainer 1, preferably cylindrical, supported in any suitable manner, such as by a bracket 2, the chamber having an open top end and a closed bottom end. A shaft 3 is longitudinally disposed in the container and is rotatably journaled in a top bearing or spider 4 at the upper end of the container and in the base member 5 thereof.

The container 1 is disposed adjacent a chute or conveyor 6, over which the cans or packages pass, having suitable guide rails 7. Keyed to the shaft 3, and lying preferably in juxtaposition with the bottom wall 5 of the container, is a circular measuring disk 8 of a diameter less than the interior of the container and having a plurality of equi-spaced concaved recesses 9 in its periphery, a ledge 10 being provided at the bottom of said recesses. Projecting obliquely into the container near the bottom thereof, is a scraper member 11, suitably housed in a casing 12, secured to the exterior wall of the container. Said scraper member is of a size and shape as to engage and scrape the inner faces of the recesses 9, as the disk is rotated by the shaft 3, and is held in contact with the walls of the recesses by means of a coil spring 13 surrounding the stem 11^a thereof and within the casing 12, the outer extremities of the stem 11^a projecting from the casing 12 in order that it may be manually manipulated, when occasion arises.

A segmental strip or block 14 is disposed on the bottom wall 5 of the container and fills the space between the ledge 10 of the disk 8 and the walls of the container and on both sides of the scraper member 11, there being an opening 15 in the segment 14 through which the scraper member extends in order to engage in the recess 9. It will be observed from Figures 3 and 4 that the ends of the segmental member 14 terminate at substantially diametrically opposite points of the container 1, and has its end surfaces bevelled as at 14^a to prevent binding or jamming of the material under the action of the rotary disk 8. A segmental plate 16, (see Figs. 1 and 3) is secured to the member 14, by means of screw members, and extends over the disk 8 in order to cover the recess 9 therein, the plate 16 being of a length substantially corresponding to the segment 14. Thus it will be seen that for

certain distance around, each of the recesses 9 forms an entirely enclosed pocket isolated from the remainder of the container.

The disk 8 rotates in the direction of the 5 arrows indicated in Figs. 3 and 4,—and forwardly of the scraper member 11, an orifice 30 is provided through the member 14, which orifice leads into an outlet or discharge chute 17, secured to the bottom wall 10 of the container and positioned to discharge the salt or other material into the cans or packages P, as they are fed along the chute 6.

A suitable agitator is provided in the 15 container and is keyed to the shaft 3 and consists of a collar 18 having radially extending arms 19. The agitator is, preferably, positioned slightly above the disk 8 in order that the contents in the container will 20 be continually fed in the recesses of the measuring disk 8 as they pass from under the plate 16. The shaft 3 may be supported in any suitable manner such, as for instance, by a collar 19 fast therein and resting on 25 the chute 6, or may be supported by a bearing 20 in which the lower end of the shaft is suitably journaled. As illustrated in Fig. 2, the shaft 3 extends below the chute 6 and has provided on its lower end a male 30 coupling 21. A shaft 22 is arranged in vertical alinement with the lower end of the shaft 3 and is provided with a female coupling member 23 to cooperate with the coupling member 21, these coupling members 35 being held together by means of relatively light pins 24, as fully illustrated in Fig. 2. Rotatably mounted on the shaft 22 is a casting 25 which is positioned adjacent the ratchet wheels 26 fast on the shaft. The 40 casting has mounted thereon a spring pressed pawl 27 positioned to engage the ratchet wheels 26. An opposite portion of the casting 25 is provided with a lug 28 to which is connected with one end of an operating link 29, having a connection with 45 the operating mechanism (not shown) of the canning machine in order that the salting device will be operated in proper sequence of time.

50 In the operation of the device, cans or packages are fed successively along the chute 6 and under the discharge spout 17. In the proper sequence of operation of the machine, the casting 25 is partially rotated 55 in the direction of the arrow, causing the pawl 27 to engage the ratchet wheels 26 and rotate the shaft 3 for a distance corresponding to the length of one of the recesses 9 in the measuring disk 8. Thus the contents of 60 one of the pockets 9, gathered while the pocket is opened to the material in the container, is discharged during the period of rotation of the shaft by the scraper member 11, through the orifice 30 and through the 65 spout 17 into the packages or cans P.

Should the measuring disk 8, or the shaft 3, become clogged, or for any reason refuse to rotate, the pins 24 will be sheared off or broken when the shaft 22 is again rotated through the link 28, thus releasing the shaft 70 3 and preventing any possible breakage from occurring.

It will thus be seen from the foregoing that the present device provides a dispensing device for packing or canning machines for 75 discharging a predetermined amount of its contents, and provides such operating means as will prevent serious damage to the mechanism upon failure of it to properly operate or function, while at the same time providing an extremely economical and simple construction.

I claim:

1. A device of the character described, comprising a container having a discharge 85 opening therein, a measuring disk within said container adjacent said discharge opening and having peripheral pockets, means for imparting a step-by-step rotation to said disk, and a scraper located contiguous to said discharge opening and positioned to engage the periphery of said disk.

2. A device of the character described comprising a container having a discharge 95 opening therein, a measuring disk within said container adjacent said discharge opening and having peripheral pockets, means for imparting a step-by-step rotation to said disk, a rod having a scraper head, and means for holding said scraper head yieldably 100 against the periphery of said disk.

3. A device of the character described, comprising a container having a discharge opening therein, a measuring disk within 105 said chamber adjacent said discharge opening and having peripheral pockets, means for imparting a step-by-step rotation to said disk, a rod having a scraper head, means for holding said scraper head yieldably against the periphery of said disk, and a cover plate located above said scraper head 110 and covering a number of said pockets.

4. A device of the character described comprising a container having a discharge 115 opening therein, a measuring disk within said container adjacent said discharge opening and having peripheral pockets, and a scraper located contiguous to said discharge opening and positioned to engage the periphery of said disk, said scraper being both 120 automatically and manually operable.

5. A device of the character described comprising a container having a discharge 125 opening therein, a measuring disk within said container adjacent said discharge opening and having peripheral pockets, a rod having a scraper head, and means for holding said scraper head yieldably against the periphery of said disk.

6. A device of the character described, 130

- comprising a container having a discharge opening therein, a measuring disk within said chamber adjacent said discharge opening and having peripheral pockets, a rod 5 having a scraper head, means for holding said scraper head yieldably against the periphery of said disk, and a cover plate located above said scraper head and covering a number of said pockets.
- 10 7. A device of the character described, comprising a container having a discharge opening in the bottom wall thereof, a rotatable disk on the bottom wall thereof having a plurality of measuring pockets in the periphery thereof and arranged to successively 15 pass contiguous to said opening as the disk is rotated, means overlying said discharge opening and the pockets in the disk adjacent the opening, and means yieldingly contacting with the periphery of the disk to be 20 pressed successively into each of said pockets, as the disk is rotated, to discharge the same of their contents through said discharge opening.

In testimony whereof I affix my signature.
JOHN F. ANDERSON.
